[57] ABSTRACT

A reciprocable piston internal combustion engine having one or more rows of cylinders with individual cylinder heads, in which two adjacent cylinder heads are by expandable screw bolts clamped to the pertaining cylinders and the crank case so that one or more expandable screw bolts common to two adjacent cylinder heads connects or connect two adjacent cylinder heads through a bridge with the crank case.

**CYLINDER HEAD CONNECTION FOR
RECIPROCATING PISTON INTERNAL
COMBUSTION ENGINES**

The present invention relates to a cylinder head connection for a reciprocating piston internal combustion engine in which the cylinders may be arranged in series or may be designed in V-arrangement with individual cylinder heads, according to which two adjacent cylinder heads are by tie rods connected to the cylinder and the crank-case.

With cylinder heads of reciprocating piston engines it is a well known fact that with increasing thermal and mechanical load, problems as to strength and deformation arise which put a limit to a further increase in the load and thereby to a further increase in the power of the engine. This limit is inherent to the limitations of the material employed. With light metal cylinder heads of air-cooled internal combustion engines, the limit of the strength of the respective material is further decreased by the construction necessary in order to accommodate the cooling system. In this connection, the arrangement of the connecting screws in the cylinder head is particularly difficult because the forces exerted by the screws connecting the cylinder head to the cylinder and the crank-case bring about considerable deformations.

It is known to arrange the connecting screws for the cylinder head, depending on the number of screws either all of them or some of them, in the locally widened separating gap between two cylinder units and to connect both cylinder heads through a disc or link simultaneously with the crank-case. In this connection it is disadvantageous that differences in height caused by manufacturing tolerances between two cylinder units will not be compensated for so that a high end pressure and additional stresses in the screws occur as a result of bending stresses.

It is furthermore known to convey screw forces through a crowned or spherical disc with corresponding counter bearings. Such an arrangement, however, has the drawback that the screw forces engage the marginal area of or in the vicinity of the cylinder head whereby, caused by the shape of the surfaces along which the cylinder head and the cylinder engage each other, a tilting moment occurs which tilts the cylinder head when unilaterally loosening the connecting screws. In this way the advantage of a facilitated assembly and disassembly of individual cylinder units is lost because all screws have to be loosened.

Finally, an air-cooled internal combustion engine has become known as disclosed, for instance, in German Pat. No. 940,075 and Motortechnische Zeitschrift 1968, Issue 4, Page 132-138, according to which the connection of the cylinder head is effected by means of expandable or necked-down bolts partially arranged in the gas passages. Such a design has the drawback that the arrangement of the screws and the shape of the passages have to be selected in accordance with each other even though the shape of the inlet passage is determined primarily by the requirement to impart a twist upon the air flowing into the cylinder. On the other hand, the screw support is arranged approximately at the level of the bottom of the cylinder head the structural height of which will in most instances with increasing thermal load of the engine not be sufficient to

absorb the bending moment caused by the screw forces. A deformation will result, especially in the region of the exhaust passages, which deformation will after a certain temperature has been reached result in permanent deformations. A decrease in the screw forces in the seal between the cylinder head and cylinder is the result.

It is, therefore, an object of the present invention so to design the screw connection of cylinder heads that this connection will have only a minor influence upon the location and shape of the gas passages while the screw force will as far as possible be directly conveyed to the abutting or pressure surfaces between the cylinder head and the cylinder.

This object and other objects and advantages of the invention will appear more clearly from the following specification in connection with the accompanying drawings, in which:

FIG. 1 illustrates a longitudinal section through a portion of an air-cooled internal combustion engine while two cylinders in upright position are shown in view.

FIG. 2 shows the two cylinder units of FIG. 1 as seen from the top and designed according to the invention.

FIG. 3 is a section through the two cylinder units, said section being taken along the line III—III of FIG. 1.

FIG. 4 shows the sealing surface of the two cylinder units of FIG. 1 between cylinder head and cylinder and also the location of the expandable screws and the points of support of the bridge.

The cylinder head connection according to the present invention is characterized primarily in that each two adjacent cylinder heads are by one or more expandable screws or necked-down bolts together connected to the crank-case by means of a bridge. In this way the arrangement of the gas changing passages (inlet and outlet passages) is substantially independent of the location of the screw or the screws. In view of the fact that the point of attack of the force of the bridge is located at a high level, the distribution of the pressure in the cylinder head becomes more favorable and the pressing force at the joint surfaces becomes more uniform. Moreover, the supporting points of the bridge are located almost vertically over the center of gravity of the fourth of the joint surface (Viertel-Fuegelaechte) between the cylinder head and the cylinder, whereby the bending moment introduced by the screw force will be low and a tilting moment will be prevented when two expandable screws are unilaterally loosened.

According to a further development of the invention, auxiliary supports are employed at the end cylinders as counter bearings for the bridges. These auxiliary supports may, with air-cooled engines, preferably be in the form of locally reinforced jackets for the cooling air.

According to a still further development of the invention, it is suggested to convey the screw forces conveyed by the bridge to the cylinder head through the intervention of crowned or spherical pressure surfaces and intermediate layers or shims according to the surface pressure, said intermediate layers being plane or concave. The crowned or spherical pressure surfaces compensate for differences in the height of the bridge support, whereas the intermediate layers compensate for displacements in all directions so that the require-

ments with regard to the precision of the location of two cylinder units are not very high. In order to obtain a more favorable flow of the forces of the screws, especially to bring about the formation of a pressure cone which will as uniformly as possible distribute the forces over the joint surface, it is suggested that the supporting points for the bridge on the cylinder head are spaced as far as possible from the joint surface and are possibly arranged on the bottom of the upper cylinder head. For purposes of conveying the pressure forces from the bridge support to the joint surface, there are preferably employed the walls of the gas changing passages or supporting walls, fins, ribs, and reinforcements while such reinforcements are designed in conformity with aerodynamic principles.

A further very simple design is obtained in view of precast chambers for the expandable screws in the cylinder and the cylinder head and, more specifically, in the form of a longitudinal groove which is so dimensioned that the flow of cooling air when passing through the separating gap will not undergo any material throttling in view of the screw shank.

For purposes of limiting the overall height of the engine, the connecting elements are preferably so arranged that they are located within the greatest structural height of the internal combustion engine as it is formed by the hood for the cylinder head.

Referring now to the drawings in detail, FIG. 1 shows two cylinders 1, 2 with cylinder heads 3, 4 according to which the cylinders 1, 2 are by means of expandable screws 5 connected to the crank-case 8 through the intervention of bridges 6 and intermediate layers or shims 7. On the outside of the cylinder units 1, 3 - 2, 4 the screw force is conveyed on one hand to the cylinder heads 3, 4 and on the other hand to the jackets 9, 10 for the cooling air, said jackets forming auxiliary supports.

According to FIG. 2, the cylinder heads 3, 4 are by means of expandable screws 5 connected to the crank-case (not shown) through the intervention of bridges 6 and intermediate layers or shims 7. On the outside of the cylinder heads 3, 4, the screw force is conveyed to the auxiliary supports forming the jackets 9, 10.

According to FIG. 3, the cylinder heads 3, 4 are at the level of the gas changing passages 11, 12-13, 14 sectioned in a direction transverse to the cylinder axis. The advantageous arrangement of the expandable screws 5 in the separating gap between two cylinder units illustrates the flexibility the designer has for designing the gas changing passages, preferably the inlet passages 11, 13, and also shows the favorable design of the fins at the very hot inner parts of cylinder head cover means 20 of the cylinder head. The direction of flow of the cooling air is indicated by arrows. The free chambers 15 for the expandable screws 5 form passages of sufficiently large dimensions for the cooling air.

FIG. 4 illustrates the joint surfaces 16 of the cylinder heads and the cylinders with their surface central lines 18. The screw forces conveyed by means of bridges are at the points 17 where the forces attack, conveyed to the cylinder head. The connecting lines 19 of the points 17 intersect the central line 18 of the joint surface 16. As a result thereof, a tilting of the cylinder head in response to a unilateral loosening or tightening of the expandable screws for assembly or disassembly pur-

poses of the adjacent cylinder head will be prevented in an advantageous manner.

Although the illustrated example shows the points 17 located in projection in pairs within and outside the central line 18, it is to be understood that the invention also includes arrangements according to which all points 17 are located within the central line 18. Similarly, the present invention comprises designs according to which the joint surfaces have a shape other than circular shape, whereas the points of attack of the forces all or partially located in the projection upon the joint surface will with an engine with the cylinders in series arrangement not result in any tilting moment toward the adjacent cylinder.

It is, of course, to be understood that the present invention is, by no means, limited to the particular showing in the drawings but also comprises any modifications within the scope of the appended claims.

What I claim is:

1. A reciprocable piston internal combustion engine, which includes: at least two serially arranged adjoining cylinders with separately detachable individual cylinder heads, a crank case associated with said cylinders, bridge means for engagement with said cylinder heads, and expandable screw means, at least one of said screw means being common to two adjacent cylinder heads with only said expandable screw means transmitting screw force by way of said bridge means upon two adjoining cylinder heads and detachably connecting said two adjacent cylinder heads individually separable from the pertaining cylinders relative to said crank case.

2. An arrangement according to claim 1, in which each of said cylinder heads includes a plurality of bridge support points, and in which the vertical projection of the connecting line of two adjacent bridge support points defines a chord with regard to the surface center line of the annular joint surface between a cylinder head and the pertaining cylinder.

3. An arrangement according to claim 1, which includes auxiliary supporting means arranged at the cylinders at the ends of said engine and forming counter bearings for the respective adjacent bridge means.

4. An arrangement according to claim 1, in which said bridge means are provided with crowned engaging surfaces facing the respective adjacent cylinder head, and in which shim means are interposed between said crowned engaging surfaces and the pertaining adjacent cylinder head surfaces.

5. An arrangement according to claim 2, in which said bridge support points of said bridge means are located on the upper surface of the pertaining cylinder head and are spaced from said joint surface as far as possible.

6. An arrangement according to claim 2, in which said engine has gas inlet and outlet passage means, and in which said bridge support points are so located that the forces introduced into the cylinder heads by said bridge means pass through the walls defining said inlet and outlet passage means.

7. An arrangement according to claim 2, in which said engine has reinforcing wall means, and in which said bridge support points are so located that the forces introduced into the cylinder heads by said bridge means pass through said reinforcing wall means.

8. An arrangement according to claim 1, in which said cylinder heads and said cylinders have cast passage means therein for the passage of said expandable screw means.

9. An arrangement according to claim 1, which includes cylinder head cover means mounted on said

cylinder heads, and in which said expandable screw means with said bridge means are located within the maximum structural height of the engine including said cylinder head cover means.
